UNITED STATES PATENT OFFICE.

MADISON D. SHIPMAN, OF DE KALB, ILLINOIS.

DESIGN FOR A BUTTON.

SPECIFICATION forming part of Design No. 32,719, dated May 29, 1900.

Application filed May 1, 1900. Serial No. 15,134. Term of patent 14 years.

To all whom it may concern:

Be it known that I, MADISON D. SHIPMAN, a citizen of the United States, residing at De Kalb, in the county of De Kalb and State of Illinois, have invented and produced a new and original Design for Buttons; and I do declare the following to be a full, clear, and exact description of the same, reference being had to the accompanying drawings, forming a part thereof.

My present invention relates to new and original designs in buttons.

In the accompanying drawings, Figure 1 is a plan view of a button, showing my new design. Fig. 2 is a side view of the same.

As shown in the drawings, my design consists of a button-head having upon its outer surface a centrally-arranged figure consisting of a series of lines radiating from a common center. At the outer terminations of the

radial lines a number of curved lines are formed. The outer termination of these curved lines end in a serrated edge. Beginning at said serrated edge and extending outward therefrom are a series of more distinct 25 lines and intermediate spaces alternately arranged.

As shown in Fig. 2, the button-head has a slightly-curved top.

The essential feature of my design consists 30 in the arrangement of three concentric rosettes.

Having thus fully described my new design, what I claim is—

The design for a button, substantially as 35 shown and described.

MADISON D. SHIPMAN.
